UNITED STATES PATENT OFFICE.

FREDERICK B. FRANKS, OF BATH, PENNSYLVANIA.

PULVERIZER.

1,363,106.

Specification of Letters Patent. Patented Dec. 21, 1920.

Application filed April 11, 1918. Serial No. 227,957.

To all whom it may concern:

Be it known that I, FREDERICK B. FRANKS, a citizen of the United States, and a resident of Bath, county of Northampton, State of Pennsylvania, have invented certain Improvements in Pulverizers, of which the following is a specification.

My invention relates to certain improvements in a pulverizer for which Letters 10 Patent were granted to me on the 7th day of November, 1916, No. 1,204,385.

One object of my present invention is to construct a yoke so that the pushing arms can be renewed, when broken, without dis- 15 carding the entire yoke structure.

A further object of the invention is to make these arms in separate castings which, when assembled, form a complete ring which can be rigidly secured to the main body of 20 the yoke.

In the accompanying drawings:—

Figure 1, is a sectional view of sufficient 25 of a pulverizer to illustrate my invention;

Fig. 2, is a detached perspective view of my improved yoke;

Fig. 3, is a plan view of the lower section;

Fig. 4, is a perspective view of the lower section;

Fig. 5, is a side view showing the lower 30 section made of a series of segments;

Fig. 6, is a vertical sectional view of the yoke illustrated in Fig. 5, through both the upper and the lower sections;

Fig. 7, is a plan view, showing the seg- 35 mental lower section; and

Fig. 8, is a perspective view of one of the segmental arms.

Pulverizers of the type illustrated are subjected to a considerable strain and shocks 40 and it often occurs that one of the pushing arms of the yoke, which propels the pulverizing balls in their circular path, breaks due to the strain to which the arms are subjected and, consequently, a new yoke has to 45 be substituted for the broken one.

I have found that, by making the section carrying the arms separate from the main body of the yoke, I can make a more perfect casting than where it is made in one 50 piece. Moreover, the section having the arms can be made of a tougher metal than the body portion of the yoke.

Referring to Fig. 1, which illustrates sufficient of a pulverizer to illustrate my in- 55 vention, 1 is a grinding ring mounted on

the intermediate section 2 supported on any suitable base. Located on the intermediate section is an upper section 4 in which is a screen 5. This type of machine is fully illustrated in the above mentioned patent. 60

6 is a vertical shaft driven in any suitable manner. This shaft extends through the projection 7 of the central section of the machine and carried by this shaft is a shou- 65 ldered support 8 on which is mounted the hub 9 of the yoke 10. The support and the opening in the hub are so formed that the yoke must turn with the shaft. The yoke is made in two sections 11 and 12; the upper section 11 is the body section and carries 70 the diagonal brackets 13 and the vertical arms 14 to which the blades 15 and 16, re- spectively, are attached. The diagonal blades lift the powdered material, as it is formed, and the vertical blades 16 catch this 75 powdered material and direct it against the screen 5.

On the lower section, in the present instance, are four arms 17 which carry the pushers 18, and mounted in front of each 80 pusher is a ball 19. The balls travel against the grinding ring 1. The lower section 12 is secured to the upper section 11 of the yoke by a series of vertical bolts 20 and, in order to relieve the bolts from strain and to couple 85 the lower arm section rigidly with the main upper section 11, I provide the upper sec- tion with a series of radial projections 21, which are spaced apart and enter recesses 22 between the radial projections 23 on the 90 lower section so that, when the parts are bolted together, the lower section is driven through the positive coupling.

In the construction shown in Figs. 1 to 4, inclusive, the four arms 17 are made integral 95 with the lower section 12, but in Figs. 5 to 8, inclusive, I have illustrated a construction in which each of the arms 17^a forms an integral part of a segment 12^a having projec- tions 23^a which interlock with projections 100 21^a on the body section 11^a, and in order to hold these sections in position against cen- trifugal action I form an annular flange 24 on the upper section, which extends into a recess 25 in each segment so that the bolts 105 20 are entirely relieved from the shearing action due to the driving of the lower sec- tion by the upper section and the centrifugal action due to the rotation of the yoke.

Thus it will be seen, by the above con- 110

struction, that I am enabled to make a much more substantial yoke for pulverizers than heretofore and one in which the parts which are likely to break can be readily replaced without discarding the entire yoke structure. I can make the arms of the lower section of different material from the body of the yoke and of a material which will withstand the strains to which the arms are subjected.

I claim:—

1. The combination in a pulverizer, of a casing having a pulverizing ring; a rotating shaft; a yoke driven by the shaft, said yoke being made in two sections, the upper section carrying a hub, diagonal brackets, and vertical arms to which blades are secured; the lower section having arms; balls driven around the ring by said arms; and means for coupling the two sections of the yoke rigidly together.

2. A yoke for a pulverizer of the type in which balls are driven over a grinding ring, said yoke consisting of upper and lower sections, the upper section carrying the hub and the lower section having arms arranged to propel the balls; and means for rigidly connecting the two sections.

3. The combination in a pulverizer of the type in which a series of balls are caused to travel over a grinding ring, of a yoke having upper and lower sections, the upper section being the main body section and having a hub and arms and brackets to which the blades are secured; the lower section having a series of rotating arms for propelling the balls; the upper section having a series of projections spaced apart and adapted to extend into recesses formed by projections on the lower section; and means for securing the two sections together.

4. The combination in a yoke for a pulverizer of the type in which the balls are caused to travel over a grinding ring, said yoke having an upper and a lower section, the upper section having a hub and a driving shaft on which the hub is mounted, the lower section consisting of a series of segments having projections interlocking with the projections on the upper section, and each segment having an arm for propelling a ball; and vertical bolts connecting the segments of the lower section with the upper section.

5. The combination in a yoke for pulverizers, of a lower section carrying a hub adapted to the driving shaft; a lower section consisting of a series of segments, each segment having an arm; a projection on each segment, said projections being less in width than the segment forming a recess; an upper section having recesses arranged to receive the projections on the segments and having an annular flange extending into the recesses of the segments; and ver-

tical bolts securing the segments to the upper section.

6. A yoke for pulverizing mills, comprising a pusher member having outwardly directed arms and also having an upwardly extending portion, a fan center separate from said pusher member having a downwardly directed portion resting upon said first mentioned portion, said fan center having means for supporting a plurality of fan blades, and means passing through said portions for securing together said fan center and pusher member.

7. A yoke for pulverizing mills, comprising a pusher member having outwardly directed arms, a fan center separate from said pusher member and resting upon the latter, interlocking projections disposed on the contacting surfaces of said pusher member and fan center, and bolts for detachably securing together said fan center and pusher member.

8. A pusher member for pulverizer mill yokes having outwardly directed arms, and an upwardly extending portion adapted to support a fan center thereon.

9. A fan center for pulverizer mills having means for supporting a plurality of fan blades, and a downwardly extending portion adapted to rest upon a pusher member.

10. A yoke for pulverizing mills, comprising a pusher member having outwardly directed arms and also having an upwardly extending portion, a fan center separate from said pusher member having a downwardly directed portion resting upon said first mentioned portion, said fan center having means for supporting a plurality of fan blades, and said portions being provided with interlocking projections preventing relative lateral movement between said pusher member and said fan center.

11. A yoke for pulverizing mills, comprising a pusher member having outwardly directed arms, a fan center separate from said pusher member and resting upon the latter, said fan center having means for supporting a plurality of fan blades, and bolts passing through said fan center and pusher member detachably securing them together.

12. A yoke for pulverizing mills, comprising a pusher member having outwardly directed arms and also having an upwardly extending portion, a fan center separate from said pusher member having a downwardly directed portion resting upon said first mentioned portion, said fan center having means for supporting a plurality of fan blades, and bolts passing through said portions and the body of the fan center and pusher member detachably securing the two together.

In witness whereof I affix my signature.

FREDERICK B. FRANKS.
